R. E. COLLINS.
CYLINDER HEAD AND METHOD OF MANUFACTURING SAME.
APPLICATION FILED APR. 24, 1920.

1,386,162.

Patented Aug. 2, 1921.

INVENTOR:

Ralph E. Collins,
By Frank H. Werner,
ATTORNEY.

UNITED STATES PATENT OFFICE.

RALPH E. COLLINS, OF INDIANAPOLIS, INDIANA.

CYLINDER-HEAD AND METHOD OF MANUFACTURING SAME.

1,386,162.

Specification of Letters Patent.

Patented Aug. 2, 1921.

Application filed April 24, 1920. Serial No. 376,230.

To all whom it may concern:

Be it known that I, RALPH E. COLLINS, a citizen of the United States, residing at Indianapolis, in the county of Marion and State of Indiana, have invented certain new and useful Improvements in Cylinder-Heads and Methods of Manufacturing Same, of which the following is a specification.

This invention relates to a cylinder head for internal combustion engines, and the general object of the invention is to provide a cylinder head of the above character which can be placed upon the market as a merchantable article of trade to be sold to the public; and made in different styles and shapes to fit engines of different manufacturers; and which can readily be placed into operative position by persons of limited mechanical skill without the use of special tools and appliances.

A further object of the invention consists in the provision of a merchantable cylinder head, as a complete article of manufacture, in which the liability of overheating is largely overcome, so that premature congealing or thickening of the oil, which ultimately results in the formation of accumulated carbon deposit, is greatly retarded.

I accomplish the above objects of the invention, and such others as may appear from a perusal of the following description and claims, by means of the construction illustrated in the accompanying drawings, forming a part hereof, in which—

Figure 1 is a top or plan view of my improved cylinder head for internal combustion engines. Fig. 2 is a view partly in side elevation and partly in longitudinal section, on the line 2—2 in Fig. 1. Fig. 3 is a transverse section on the line 3—3 in Fig. 2.

Referring to the drawings the cylinder head comprises an integrally formed unit member 10 of sufficient width and length to close the open ends of the several cylinders of the engine, whether these comprise four or twelve in number, which head is composed of metal of a character usually employed in the manufacture of cylinder heads. Head 10 is securely attached to the cylinder block in the usual way by means of bolts which pass through the openings 11, and these openings register with the threaded holes in the cylinder block for the attachment of usual individual cylinder heads. 12 represents the openings for receiving the spark plugs. Head 10 is pro-

vided on its upper surface with a series of longitudinally disposed integral ribs or fins 15, which as shown in Fig. 2, extend some distance above the upper surface of head 10. Ribs 15 are arranged so as to provide intervening channels 16 for the passage of air, and the ribs are slightly tapered and arranged to bring their thinnest parts adjacent the end of the head where the air discharges from channels 16. This construction of ribs 15 increases the width of the channels 16 as they approach their discharge ends and assists in overcoming the frictional resistance and resulting retardation in the movement of the air imposed by the surface area of uniformly formed ribs. This tapering of ribs 15 removes in whole or in part sluggishness or retardation in the movement of the air through channels 16, so that a greater amount of air is induced to travel through channels 16 in a given period of time than would otherwise obtain, and which results in removing and carrying away a correspondingly larger amount of heat from the cylinder head, and promoting a condition which greatly retards the formation and accumulation of carbon, than prevails in the conventional types of cylinder heads in common use.

The device is so simple that further description thereof is deemed unnecessary.

Having thus fully described my said invention, what I desire to secure by Letters Patent, is—

1. As an article of manufacture a cylinder head for internal combustion engines comprising a single unit member having a plurality of thin integrally formed ribs arranged longitudinally of the cylinder head to form air passageways, said ribs being tapered from one end to the other.

2. As an article of manufacture a cylinder head for internal combustion engines comprising a unit member having a plurality of comparatively thin ribs extending vertically from its top surface, said ribs tapering in thickness from one end to the other to form intervening air passageways having their maximum width at their discharge ends, said head being provided with suitably located apertures for securing the head and for attaching the spark plugs.

In witness whereof, I, have hereunto set my hand and seal at Indianapolis, Indiana, this 16th day of April, A. D., one thousand nine hundred and twenty.

RALPH E. COLLINS. [L. s.]
